UNITED STATES PATENT OFFICE.

SAMUEL I. TRASK, OF GUILFORD, NEW YORK.

FIRE-ESCAPE.

SPECIFICATION forming part of Letters Patent No. 352,211, dated November 9, 1886.

Application filed June 26, 1886. Serial No. 206,289. (No model.)

To all whom it may concern.

Be it known that I, SAMUEL I. TRASK, a citizen of the United States, residing at Guilford, in the county of Chenango and State of New York, have invented certain new and useful Improvements in Fire-Escapes; and I do hereby declare that the following is a full, clear, and exact description of the same, reference being had to the annexed drawings, making a part of this specification, and to the letters and figures of reference marked thereon.

Figure 1 of the drawings is a perspective view of a window, showing the application of my invention thereto; and Fig. 2, a detail view, partly in section, of the stationary pulley and its connections.

The present invention has relation to certain new and useful improvements in fire-escapes; and it consists in the details of construction substantially as shown in the drawings and hereinafter described and claimed.

In the accompanying drawings, A designates the usual window-casing or frame, to the upper portion of which I attach my stationary pulley.

The essential feature of my invention consists in the means employed for attaching the pulley to the window-casing or frame, whereby it will support the necessary weight when a person is descending from a window, and this without danger of the pulley coming loose from its fastening, which has heretofore been an objection to this class of fire-escapes.

The pulley, as shown at B, has a grooved periphery of V-shaped form, as shown at a, which not only forms a guide for the rope b, but forms a means for wedging said rope tight between the sides of the V-shaped groove when it is desired to stop the descent of the person in the carriage or sling C for any purpose.

The pulley B is preferably of semicircular shape, and has secured to its sides metal plates D, which extend up above the periphery of the pulley, and have guide-rod c passing through the plates and extending transversely over the periphery of the pulley, to form keepers for retaining the rope b within the groove a, and also to form braces for the projecting edges of the plates D. These plates protect the pulley by forming a shield thereto, as well as increasing the strength of the device. To one side of the plates D (preferably the

outer side) are securely fastened hanger E and hangers F, the former being bent outwardly in a horizontal direction, thence upwardly in 55 a vertical direction, thus forming a right-angle bend, d, as shown in Fig. 2, in order to allow the pulley B to come as near the window-sashes as possible, and at the same time attach the bracket E to the upper and outer side of 60 the window-frame A by suitable screws. The hangers F extend outwardly at an angle to each other, and have their upper ends bent horizontally in an outward direction, as shown at e, for the purpose of attaching said hangers 65 to the under side of the casing A by screws, which extend up vertically into the same. By means of the arrangement and peculiar construction of these hangers the pulley is firmly held to the window-casing or frame by means 70 of the screws which pass into the same both horizontally and vertically, thereby forming a complete fastening for the pulley, without danger of its becoming loose by the usual weight upon the rope in the descent of the person.

The carriage, sling, or hammock C may be of any desirable form or construction, and is connected to the rope b by ropes f, a steady-cord, g, being connected to the ropes f. If preferred, three or more of the hangers may 80 be used, as found desirable; also a hook, h, may be connected to one end of the steady-cord g, so that means may be attached thereto for preventing sick persons or children from falling out of the hammock. When not in use, the 85 hammock with its attachments may be disconnected from the pulley and placed in a case at the upper corner of the window-frame out of the way.

It is evident that any suitable carriage, sling, 90 or hammock may be used and connected in any suitable manner to the rope b, and when preferred a guy-rope may be attached thereto and extend down to the pavement or ground, to steady the hammock when descending.

The pulley with attachments may be manufactured and placed in the market at a greatly-reduced cost, and ready for attachment by screws to the window-frame, and when thus attached the pulley will depend or be located 95 directly under the window-frame, instead of upon the outside, thereby bringing the rope within convenient reach of the occupant of the room.

Having now fully described my invention, what I claim as new, and desire to secure by Letters Patent, is—

In a fire-escape, the combination, with a suitable hammock and lowering-rope, of a pulley having a V-shaped groove on its periphery, metal plates connected to its sides and projecting above the grooved periphery, guide-rods passing through the plates and extending transversely across and over the same, and hangers secured to the plates, the hangers upon one side being bent horizontally at their upper ends

and disposed at an angle to each other, and the opposite hanger bent to form an elbow or right-angle bend, substantially as and for the purpose set forth. 15

In testimony that I claim the above I have hereunto subscribed my name in the presence of two witnesses.

SAMUEL I. TRASK.
